UNITED STATES PATENT OFFICE.

VERA HAVEMEYER, OF NEW YORK, N. Y.

SANDAL CASE.

Application filed September 12, 1925. Serial No. 55,947.

My invention relates to a sandal case and more particularly to one which is adapted to be attached to and carried in common with another article such as an umbrella, or it 5 may be carried in a hand bag or in any other convenient manner.

I am aware that great inconvenience has been caused by one wearing sandals having no convenient method of carrying them in 10 the event that they are no longer needed for protection against rain or moisture, and my invention aims to provide a convenient and satisfactory case whereby such sandals may be carried conveniently and unob- 15 trusively.

The objects and benefits of my invention will be better understood from the following specification of which the drawings form a part.

20 In these drawings I show in

Figure 1 a rear view of the case showing a method of application of the attaching members;

Figure 2 a front elevation of the case;

25 Figure 3 shows the application of the case to an umbrella;

Figure 4 is a top plan view of the case; and

Figure 5 is a front elevation of the case 30 with its lower portion folded within the upper portion.

In the preferred embodiment of my invention I have a case member 1 which is so constructed that it conveniently holds a 35 pair of sandals such as 2, 3, shown in Figure 2. The case member 1 has a lid or closure 4 adapted to fit over and be retained by suitable means such as the strap 5 held by the buckle 6. This closure member is 40 hinged as at 7. On the back of the case member I prefer to place two attaching members or straps 8 and 9, which may be slidably held by a strap or the like 10 affixed to the case member 1. While I show these 45 members 8 and 9 as straps, it will be obvious that many other attaching members may be used, depending upon the type of article to which the sandal case is to be affixed.

I prefer to form the case member 1 of 50 waterproof material, but it may equally well be made of many other materials, and in some instances the lower portion which I have designated as 1^a may be of somewhat softer material than the upper portion, so

that the former may be folded within the 55 latter when the case is empty, and thus reduce its size and contribute to the convenience of carrying.

One application of my invention is shown in Figure 3, where the straps 8 and 9 are 60 buckled about an umbrella handle 11, and from this it will be seen that my invention has a very novel and practical use, for when not in use the sandals are safely held in the case out of the way of the owner, and are 65 instantly available in case of need.

The case as a whole being comparatively small in size, the straps 8 and 9 may be removed and the case carried in a hand bag or the like without damage to the other 70 contents of the hand bag, and still have the sandals immediately available for use and out of the way when not in use. It will be apparent that the strap 10 which is disposed longitudinally of the case throughout 75 the stiffened area thereof reinforces said case and also constitutes loops for the straps 8 and 9. Additionally, this strap 10 at its upper end functions as a hinge for the lid or closure 4. In other words, the strap 80 10 serves a triple function by reason of its application and that is the reinforcing element for the case 1, loops for the securing of straps 8 and 9 and the hinge 7 for the lid or closure 4. 85

It will be understood that my invention is susceptible of many changes and variations which may be made without departing from the spirit thereof, and all such changes and variations I desire to include within the 90 scope of my claims.

I claim:

1. A case of the character described, comprising a case member having a body closed at one end and open at its other end, a swinging lid at the open end of the body, a strap longitudinally secured to the body and having its outer end swingingly connecting the lid with the body, and securing elements 95 slidably engaged transversely in said strap for the connection of the case with an umbrella handle, said body for a major portion of its length being of greater rigidity than the remaining portion thereof.

2. A sandal case, comprising in combination a container having an elongated relatively rigid body portion and a flexible bottom portion, said flexible bottom por-

tion being adapted to fold up into said body portion to thereby considerably shorten the overall length of said container, said container being adapted to hold a pair of sandals when said body portion is extended, a lid for said container and means reinforcing a major part of the body portion

and forming a hinge connection for the lid, and a holder for fasteners to permit the body to be secured to a support. 10

In testimony whereof, I have signed my name to this specification this 11th day of September, 1925.

VERA HAVEMEYER.
